INTERNAL-COMBUSTION ENGINE

Application filed January 14, 1928. Serial No. 246,665.

This invention relates to internal combustion engines and refers more particularly to improved means for the distribution and circulation of the cooling medium such as water.

5 My invention is primarily adapted for use in sleeve valve or like engines but may also be used to advantage in other types of engines.

It is desirable especially in sleeve valve engines and the like to provide a flow of the cooling water or other cooling medium in the cylinder water jacket upwardly mainly along one side of the engine such as the exhaust side and thence to the cylinder heads and outlet 15 header or to other points in the system.

One object of my invention resides in the provision of a cylinder block or engine body constructed to distribute the circulating water whereby the engine cylinders are substantially equally cooled. A further object 20 of my invention resides in a novel means for efficiently cooling the engine with particular reference to the exhaust side which tends to reach a considerably higher temperature than the intake side.

In carrying out the objects of my invention I have provided a jacketed cylinder block constructed to regulate the amount of cooling water for each cylinder and for each 30 cylinder head with respect to the proximity of the respective cylinders to the water circulating pump. Thus by varying the effective passages through which the water passes upwardly of the cylinder block preferably at the cylinder exhaust ports so that the passages nearest the water pump are smaller than the passages remote from the pump where the water supply is ordinarily less, I am enabled to efficiently distribute the 40 circulating water substantially equalizing the cooling effect for the various cylinders. My construction is of a simple nature capable of being manufactured at no greater cost than conventional cylinder blocks.

Further objects of my invention reside in the combination and arrangement of parts as hereinafter described and claimed.

In the drawings in which like reference 50 characters indicate corresponding parts,

Fig. 1 is a top plan view of the cylinder block,

Fig. 2 is a sectional elevation view along 2-2 of Fig. 1,

Figs. 3^a and 3^b together are sectional views 55 longitudinally through the cylinder block along 3^a-3^b of Fig. 2,

Fig. 4 is a detail sectional view along 4-4 of Fig. 3^a, and

Fig. 5 is a detail sectional view along 5-5 60 of Fig. 3^b.

Referring to the drawings reference character A represents the cylinder block casting or engine frame portion having a plurality of cylinders 10 and suitable intake ports 11 and exhaust ports 12 adopted to be controlled in a well known manner by one or more sleeve valves (not shown) generally located within the cylinders. The particular type and construction of the sleeve valve or 65 valves forms no part of this invention.

The cylinder block A is formed with a jacket 13 permitting circulation of cooling water around the cylinders 10. Extending transversely of the cylinder block are spaced walls 75 14 and 15 respectively forming the floor and ceiling of the intake chambers 16 and the exhaust chambers 17, these chambers being respectively in communication with the cylinder ports 11 and 12 and being respectively 80 open at 18 and 19 for communication with suitable intake and exhaust manifolds (not shown).

Located at some convenient point is a water pump 20 having a water inlet 21 and an outlet 22 to the jacket 13 preferably below the lower wall 14. Cooling water from the pump 20 circulates longitudinally of the engine cooling the cylinders 10. The cylinder block A is provided with openings 23 communicating with the jacket 13 affording an outlet for the water which thereafter may be conducted through the usual cylinder heads (not shown) and thence to the usual header 24 usually extending longitudinally along the 95 intake side of the engine to the cooling radiator.

Along the exhaust side of the engine I have provided longitudinally spaced passages 25 or cores through the walls 14, 15, these pas- 100

sages affording passage of cooling water from the lower portion of the jacket 13 to the cylinder block outlets 23. By varying the size of the passages, the cooling water may be caused to be efficiently circulated along each 5 cylinder and to be efficiently distributed to the outlets 23 and thence to the cylinder heads (not shown). Thus from Figs. 2, 3^a, and 3^b, it will be noted that the passages 25 nearest the pump 20 are smaller than the passages 10 more remote from the pump where the water supply is ordinarily less, resulting in an efficient distribution substantially equalizing the cooling effect for the various cylinders. My invention thus provides means 15 for restricting the flow of cooling water for the cylinder or cylinders nearest the source of supply of the cooling water. For illustration I have shown the passages 25 substantially progressively increasing in effective cross-sectional area according to their 20 remoteness from the pump, although in actual practice the variation need not be so marked as will be readily understood.

The intake side of the engine may also be 25 provided with openings 25^a principally to provide a relatively small quantity of water to circulate upwardly of the jacket 13 on the intake side to prevent formation of steam pockets. The greater quantity of water is 30 preferably circulated from jacket 13 through outlets 23 along the exhaust side of the engine where greater cooling is required. From the openings 23 along the exhaust side of the engine the water passes transversely of the 35 cylinder heads (not shown) to the header 24 as will readily be understood.

Where the water pump is located intermediate the ends of the cylinder block appropriate adjustment may be made in the relative sizes of the passages 25 for the cylinders 40 in proximity to the pump and for the cylinders remote from the pump as will be readily understood.

By restricting the passage of the cooling 45 water or other cooling medium within the cylinder block jacket, the upper face of the cylinder block may be provided with relatively large openings 23 along each longitudinal side of the cylinder block facilitating in the 50 coring operations of the cylinder block as will be readily understood.

What I claim as my invention is:

1. An internal combustion engine of the sleeve valve type comprising in combination 55 a cylinder block having a plurality of water jacketed engine cylinders, a pump circulating the cooling water in said water jacket, water outlet means for conducting water from the 60 water jacket, cylinder block chambers positioned across the path of the water circulating from the pump to the said water outlet means, passages through said chambers affording passage for the cooling water 65 during travel thereof from the pump to the

water outlet means, said passages being constructed and arranged to substantially equalize the cooling effect for the cylinders.

2. An internal combustion engine of the sleeve valve type comprising a cylinder block composed of a plurality of jacketed engine cylinders, intake and exhaust gas conduits for the cylinders respectively arranged on opposite sides of the cylinder block, a pump for circulating cooling fluid through the cylinder jacket, cylinder block outlet means for the cylinder jacket cooling fluid, and cooling fluid circulating means proportioned with respect to proximity to the pump for regulating the cooling effect of the cylinders along 70 the exhaust side of the cylinder block. 75

3. An internal combustion engine of the sleeve valve type comprising a cylinder block composed of a plurality of jacketed engine cylinders, intake and exhaust gas conduits for the cylinders respectively arranged on opposite sides of the cylinder block, a pump for circulating cooling fluid through the cylinder jacket, cylinder block outlet means for the cylinder jacket cooling fluid, and a plurality of passages through which the cooling fluid passes from the pump to the cylinder block outlet means, said passages along the exhaust gas conduit side of the cylinder block varying in effective cross-sectional area in 80 relation to their proximity to the pump. 85

4. An internal combustion engine of the sleeve type comprising a cylinder block composed of a plurality of jacketed engine cylinders, intake and exhaust gas conduits for the cylinders respectively arranged on opposite sides of the cylinder block, a pump for circulating cooling fluid through the cylinder jacket, cylinder block outlet means for the cylinder jacket cooling fluid, and a plurality of passages through which the cooling fluid passes from the pump to the cylinder block outlet means, said passages being spaced longitudinally of the cylinder block along the 90 exhaust side thereof, the passages relatively 95 remote from the pump having greater fluid conducting capacity than the passages in proximity to the pump. 100

5. An internal combustion engine of the sleeve type comprising a cylinder block composed of a plurality of jacketed engine cylinders, intake and exhaust gas conduits for the cylinders respectively arranged on opposite sides of the cylinder block, a pump for circulating cooling fluid through the cylinder jacket, cylinder block outlet means for the cylinder jacket cooling fluid, and a plurality of passages through which the cooling fluid passes from the pump to the cylinder block outlet means, said passages being spaced longitudinally of the cylinder block along the 110 exhaust side thereof, the passages relatively 115 remote from the pump having greater cross-sectional area than the passages in proximity 120 to the pump. 125

6. An internal combustion engine comprising in combination a plurality of engine cylinders, cooling fluid jacketing means for the cylinders, cooling fluid inlet and outlet means for the jacketing means, cylinder communicating chambers within the cylinder block, and means associated with said chambers interposed in the jacketing means intermediate the inlet and outlet means for substantially equalizing the cooling effect for the cylinders.

7. An internal combustion engine comprising in combination a plurality of engine cylinders, cooling fluid jacketing means for the cylinders, cooling fluid inlet and outlet means for the jacketing means, and means interposed in the jacketing means intermediate the inlet and outlet means for causing the greater portion of the cooling fluid to flow upwardly of the cylinders along one side of the engine in substantially equal quantities longitudinally of the engine.

8. An internal combustion engine comprising in combination a water jacketed cylinder block having a plurality of engine cylinders, a pump supplying water to said jacket, water outlet means for the cylinder block, a wall transversely of the cylinder block in the path of the water circulating from the pump to the cylinder block outlet means, said wall provided with water passages graduated with respect to their proximity to the pump.

9. An internal combustion engine comprising in combination a water jacketed cylinder block having a plurality of engine cylinders, a pump supplying water to said jacket, water outlet means for the cylinder block, a wall transversely of the cylinder block in the path of the water circulating from the pump to the cylinder block outlet means, said wall provided with water passages spaced longitudinally of the cylinder block, the effective cross-sectional areas of the passages being less for those passages near the pump than for those passages remote from the pump.

10. In an internal combustion engine comprising in combination a water jacketed cylinder block having a plurality of engine cylinders, a pump supplying water to said jacket, water outlet means for the cylinder block, a wall transversely of the cylinder block in the path of the water circulating from the pump to the cylinder block outlet means, said wall provided with water passages spaced longitudinally along opposite sides of the cylinder block, the accumulated effective cross-sectional areas of the passages along one side of the cylinder block being much smaller than the accumulated effective cross-sectional areas of the passages along the other side of the cylinder block.

11. An internal combustion engine comprising in combination a water jacketed cylinder block having a plurality of engine cylinders, a pump supplying water to said jacket,

water outlet means for the cylinder block, a wall transversely of the cylinder block in the path of the water circulating from the pump to the cylinder block outlet means, said wall provided with water passages spaced longitudinally along opposite sides of the cylinder block, the accumulated effective cross-sectional areas of the passages along one side of the cylinder block being much smaller than the accumulated effective cross-sectional areas of the passages along the other side of the cylinder block, the passages along the last said side of the cylinder block varying in cross sectional area with respect to their proximity to the pump.

12. An internal combustion engine of the sleeve valve type comprising in combination a cylinder block having a plurality of water jacketed cylinders, the upper face of said block having water outlets communicating with the cylinder block jacket, water inlet means for the jacket, and means in the cylinder block jacket below the said upper face for distributing the cooling water prior to passage thereof to the said outlets, said distributing means restricting the cooling water flow in the vicinity of the jacket inlet means with respect to the cooling water flow in portions of the cylinder jacket remote from the jacket inlet means.

13. An internal combustion engine of the sleeve valve type comprising in combination a cylinder block having a plurality of water jacketed cylinders, a pump located at one end of the cylinder block for supplying water to the jacket, water outlet means for the cylinder block, and a plurality of jacket passages below the water outlet means graduated with respect to their proximity to the pump, said passages being spaced longitudinally of the cylinder block for conducting water from the pump to the cylinder block water outlet means.

14. An internal combustion engine of the sleeve valve type comprising in combination a cylinder block having a plurality of water jacketed cylinders, a pump located at one end of the cylinder block for supplying water to the jacket, water outlet means for the cylinder block, and a plurality of jacket passages below the water outlet means graduated with respect to their proximity to the pump, said passages being spaced longitudinally of the cylinder block for conducting water from the pump to the cylinder block water outlet means, the passages substantially progressively increasing in effective cross-sectional area toward the end of the cylinder block remote from the pump.

In witness whereof, I hereunto subscribe my name this 7th day of January, A. D. 1928.

ARCHIE MACPHAIL NIVEN.
